GARMENT PRESS

John L. Card, Baltimore, Md., assignor to United States Hoffman Machinery Corporation, New York, N. Y., a corporation of Delaware

Application June 21, 1929. Serial No. 372,684

17 Claims. (Cl. 68—9)

This invention relates to garment presses, particularly that type of garment press in which final application of pressure is effected by means of power driven mechanism. In power driven presses it has been found desirable to first position one of the pressing elements with respect to the other pressing element by a manual operation, the power mechanism being actuated only after the pressing elements have been brought into cooperative relation. This not only enables the operator properly to lay the garment or material on the lower press element but safeguards the operator inasmuch as the application of pressure by power cannot be effected until the operator's hands have been withdrawn from between the pressing elements.

It is an object of the present invention so to construct a press of the type referred to above that a final pressure may be applied by a power actuated member cooperating with a guide or wedge member on the frame of the press.

It is another object of the invention to provide means on the press acting to prevent application of a final heavy pressure except when the upper press element or head has been lowered into pressing relation with the lower fixed element or buck.

It is a further object of the invention to provide a clutch connection between the pressure applying member and the power mechanism, the clutch being effective to connect the pressure applying member and power mechanism when the head and buck are in pressing relation and maintain the pressure for any desired period. The following description of one form of the invention illustrates its application to a garment press, reference being had to the accompanying drawings, in which:

Fig. 1 is a side elevation, partly in section, of a press embodying the several features of the invention;

Fig. 2 is a view similar to Fig. 1, the press head being shown as positioned immediately above the buck, having been lowered manually by the operator;

Fig. 3 is a view of a portion of the press corresponding with Fig. 2 except that the parts are shown in their respective positions at the moment maximum pressure is being applied;

Fig. 4 is a top sectional view of the press head lever and pressure applying mechanism taken on line 4—4 of Fig. 2;

Fig. 5 is a perspective view of the press head lever and the pressure applying arm;

Fig. 6 is a sectional view taken on line 6—6 of Fig. 2;

Fig. 7 is a sectional view of the clutch for connecting the power mechanism to the pressure applying arm taken on line 7—7 of Fig. 8;

Fig. 8 is a sectional view taken on line 8—8 of Fig. 7;

Fig. 9 is a sectional view of a portion of the clutch taken on line 9—9 of Fig. 7; and

Fig. 10 is a side elevation of a safety device 65 for the power mechanism, certain of the parts being broken.

The press includes the usual base or frame 11 supporting a table 12 and a fixed pressing element or buck 13. A movable pressing element or head 14 is secured to a swingable forked lever 15 fulcrumed at 16 on the standard portion 11' of the press frame. The head may be lowered into pressing position manually by the operator, a handle 17 being provided for this purpose, and usual pressing operations may be effected by means of a foot lever 18 connected to lever 15 by a link 19. The head is normally held in its elevated position, as shown in Figs. 1 and 4, by springs 21 each connected at one end to the lever 15 and at its other end to the frame 11 holding the press open except when it is lowered by the operator or during the application of pressure by power. The above described construction is well known in the art and further description of the details is unnecessary.

Disposed above the standard 11' of the press frame is an arched member or yoke 22, one leg of which is pivotally secured at 23 to the standard, the other or forward leg 22' being yieldingly connected to an arm 24 of the standard. The yielding connection comprises an eye-bolt 25 having its eye portion 26 cooperating with a pin 27 on the arm 24 and its other end adjustably threaded to a nut 28, the latter bearing against a heavy coiled spring 29. The leg 22' has a cup-shaped portion 30 projecting forwardly therefrom, and an annular shoulder 31 therein forms a bearing for spring 29 disposed in the cup portion and surrounding the eye-bolt 25 which passes through 100 the cup-shaped portion. A threaded plug 32 closing the top of the cup permits adjustment of the initial tension of spring 29 and provides a guide for nut 28. The leg 22' is normally spaced from arm 24 by means of an auxiliary spring 33 which holds the yoke 22 away from the arm.

The yoke 22 and the lever 15 are each substantially T-shaped in cross-section, their flanges being oppositely disposed and machined to form tracks which cooperate respectively with rollers 110

34, 35 rotatably mounted on a pin 36 journalled in bearings 37 in the end of a forked connecting rod 38. The leg 22' is widened at its ends and its lower track or flange 39 is inclined to the horizontal when the press is closed to form a wedge shaped guide, the purpose of which will be described hereinafter. The inner side of leg 22' and the upper portion of the yoke 22 are also inclined to the horizontal but in a direction opposite to the inclination of the flange 39, thus forming a recess 40 in the yoke.

The connecting rod 38 is adapted to be reciprocated by power means which in the present instance comprises an electric motor 41 secured to the rear portion of the lever 15. As stated, hereinbefore, it is desirable to apply pressure by power only when the press is closed and to maintain the pressure for any desired period. A suitable clutch mechanism is therefore interposed between the connecting rod and the motor, the clutch being capable of effecting a connection between the connecting rod and motor when it is desired to apply or release pressure on the press head. As shown in Figs. 7 and 8, the motor shaft 42 is provided near one end thereof with a worm 43 meshing with worm gear 44 keyed or otherwise secured to a sleeve 45. This sleeve has at one end a reduced portion 46 which is journaled in the cover plate 47 of the clutch housing 48. At its other end the sleeve is enlarged and milled to form ratchet teeth 49. A crank shaft 51, having crank arms 52, passes through the clutch housing and secured to this crank shaft is a plate 53 on which is pivotally supported a pawl 54 adapted to engage the ratchet teeth 49. The pawl is fastened intermediate its ends to a pin 55 journalled in the plate 53 and segment 56, the latter being fastened to the plate. As shown in Fig. 9 the spring 57 is fastened at one end to the clutch housing and at its other end to a disk 58 secured to pin 55 and resting on an annular flange 59 on the plate, the flange forming a housing for the spring. The function of spring 57 is to hold the pawl in engagement with the ratchet teeth unless otherwise constrained.

Mounted on one end of the pawl is a roller or cam follower 61 which rides on an annular cam ring 62. The cam ring has two projecting portions or high surfaces 63, 64, each of which engages the roller 61 at certain stages of the operation to disengage the pawl and teeth. The outer periphery of the cam ring is concentric with crank shaft 51 and mounted in the clutch housing for circumferential movement therein. The ring is prevented from being displaced laterally by a shoulder 65 on the housing and segments 66 removably secured to the housing 48 by means of screws 67. For the purpose of shifting the cam ring circumferentially a forked rocker arm 68, cooperating with a pin 69 on the ring is provided. The rocker arm is secured to one end of a rocker shaft 71 journalled in a boss 72 on the clutch housing, a second rocker arm 73 being fastened to the shaft 71 at its other end, and exteriorly of the housing. A link 74 connects arm 73 with a bell-crank lever 75 pivotally secured to the forward end of lever 15, and having a handle 76 thereon. By depressing handle 76 it is obvious that the ring 62 will be shifted in a clockwise direction. It is to be noted that the ring is provided on its under side with a recess 77 forming shoulders 78, 78' adapted to cooperate with an abutment 79 on the housing to limit the circumferential movement of the ring in each direction.

The rocker arm is normally held in the position

indicated in Figs. 1 and 7, that is, to the left of the center of the clutch, by a coil spring 81 fastened to the clutch housing and to the rocker arm 73. In this position the shoulder 78 on the cam ring rests against the abutment 79 and the high surfaces 63, 64 of the cam are positioned to engage the cam follower at a time when the crank arms are on dead center with respect to connecting rod 38.

Extending forwardly and downwardly with respect to the fulcrum of lever 75 and formed integrally with the lever is an arm 82 having a roller 83 at the end thereof. Secured to or cast on the frame arm 24 is a cam piece or abutment 84 designed to prevent actuation of lever 75 and the clutch until the head has been lowered manually a sufficient distance to preclude insertion of the operator's fingers between the head and buck, that is, when the space between the head and buck is less than average finger thickness. This arrangement obviates the danger of injury to the operator's hands. It is to be noted that the abutment 84 is so shaped that lever 75 cannot be rocked in any of the positions of the press head lever between its normally open position and in a lowered position in which the press is spaced but a slight distance from the buck. If the clutch is actuated when the press is in its normally open position roller 34 will ride up the inclined face of leg 22' to open the press still further. When the press head has been lowered sufficiently to permit roller 83 to clear the vertical face of abutment 84 the roller follows the under arcuate face of the abutment, thus permitting lever 75 to be rocked. Since the head is maintained in pressing relation with the buck after the clutch has been actuated to advance rollers 34, 35, it is apparent that, when it is desired to withdraw these rollers, the lever can again be rocked to cause reengagement of the clutch members, roller 83 being disposed beneath abutment 84.

From the above description it is apparent that heavy pressure can be applied to the press head only after the head has been lowered to pressing position. So long as the head is raised the connecting rod and pressure rollers will enter recess 40, if connected to the motor, the flanges of the lever 15 being above the surface 39 on the under side of the leg 22'. It is necessary, therefore, to lower the head sufficiently to form a space between the flanges on the press head lever and the under surface 39 to leg 22', substantially equal to the diameter of the rollers 34, 35. When the head has been lowered to a position at which the rollers 34, 35 are permitted to travel forward and under the surface 39, and roller 83 has cleared the vertical face of cam 84, the handle 76 is depressed, whereupon the cam ring 62 is shifted in a clockwise direction to displace the high portion 63 with respect to the cam follower. This permits the spring 57 to rock the pawl into engagement with the ratchet teeth 49 and rotate the crank shaft 51. The connecting rod 38 will then be moved forwardly and the rollers 34, 35 will exert a pressure on the lever 15, corresponding with the initial compression of spring 29, the inclined track 39 causing relative movement between the leg 22' and lever 15. The spring 29 is sufficiently strong to permit application of relatively great pressure on the goods between the pressing elements 13, 14, but will yield if further downward movement of the press head is resisted.

When the connecting rod has reached its maximum forward displacement, that is, when the

crank arms are on dead center, maximum pressure is transmitted to the press head. At the same time, the plate 53 will have moved through 180° and the cam follower will then engage the high surface 64 of the cam to release the pawl from engagement with teeth 49. The rollers 34, 35 will therefore remain stationary in their furthest forward position, it being assumed that lever 75 has been released. When it is desired to release the pressure, the handle 76 is again depressed to displace cam surface 64 and permit reengagement of the pawl and ratchet teeth. The rollers 34, 35 are then withdrawn by rearward movement of the connecting rod and when the crank arms reach their rearwardmost position with respect to the yoke 22, the cam follower engages the projection 63 on the cam to disengage the pawl and ratchet and bring the connecting rod 38 to rest. The above cycle of operations is repeated for each pressing operation.

It will be apparent that, as compared with other power presses, the present machine provides for greater accessibility of working parts, more convenient location of garment thickness adjustment and lower power requirements. The maximum pressure established when the rollers are at their maximum forward position can be readily regulated by adjustment of the plug which initially compressed the spring in the yielding connection between the lever and yoke.

While the embodiment of the invention illustrated and described is to be preferred, the details may be readily changed without affecting the novel arrangement and operation of the constituent parts of the press.

What is claimed is:

1. A garment press comprising in combination a frame; a fixed pressing element; a movable pressing element adapted to be moved into pressing relation with said fixed pressing element; carrying means for said movable pressing element; power means; guide means on said frame and disposed above said fixed element; and means actuated by said power means bearing directly against and movable along said guide means and said carrying means to move said movable element into pressing relation with said fixed element.

2. A garment press comprising in combination a frame; a fixed pressing element; a press lever; a second pressing element on said press lever and adapted to be moved into pressing relation with said fixed pressing element; power means; a guide member on said frame, said guide member having an inclined surface disposed above said fixed element; means movable into cooperative relation with said inclined surface and said lever to move said lever downward; and a releasable connection between said last mentioned means and said power means.

3. A garment press comprising in combination a frame; a fixed pressing element on said frame; a press lever having a second pressing element thereon, said second pressing element being movable into pressing relation with said fixed element; power means; guide means on said frame, said guide means being disposed intermediate the open and closed positions of said second element; and means actuated by said power means and cooperating with said lever and said guide means to apply pressure to the movable element when said second element is in closed position.

4. A garment press comprising in combination a fixed pressing element; a movable press lever having a second pressing element thereon; a

guide on the frame; and reciprocable means cooperating with said guide and the upper surface of said lever for applying pressure to said second pressing element when moved longitudinally of the lever.

80

5. A garment press comprising in combination a fixed pressing element; a movable press lever having a second pressing element thereon; a guide on the frame; power means; reciprocable means adapted to coact with said guide and the upper surface of said lever for applying pressure to said second pressing element longitudinally of the lever; and means for connecting said power means to said pressure applying means to reciprocate said reciprocable means.

85

6. A garment press comprising in combination a fixed pressing element; a movable press lever having a second pressing element thereon; power means; means adapted to coact with the upper surface of said lever for applying pressure to said second pressing element; a clutch for connecting said power means to said pressure applying means; and means on said clutch for disconnecting said power means from the pressure applying means during maximum application of pressure.

90

7. A garment press comprising in combination a frame; a fixed pressing element; a movable press lever having a second pressing element thereon; a guide on said frame; means adapted to coact with said guide and the upper surface of said lever for applying pressure to said second pressing element; and power means for moving said pressure applying means into coacting relation with said guide and lever.

105

8. A garment press comprising in combination a frame; a fixed pressing element on said frame; a movable press lever fulcrumed on said frame and having a second pressing element thereon; a reciprocable member cooperating with said lever; a guide member disposed above and secured to said frame, said guide means having a guiding surface thereon for said reciprocable member to effect relative downward movement of the press lever; and means for reciprocating said reciprocable member.

110

9. A garment press comprising in combination a frame; a fixed pressing element on said frame; a movable press lever fulcrumed on said frame and having a second pressing element thereon; a reciprocable member cooperating with said lever; means for reciprocating said member; a yoke disposed above and secured to said frame, said yoke having means thereon for guiding said member during reciprocation thereof to effect downward movement of the press lever when said second pressing element is in pressing relation with said fixed pressing element; and other means on said yoke for guiding said member when the press lever is in raised position to prevent downward movement of the lever.

125

10. A garment press comprising in combination a frame; a fixed pressing element on said frame; a movable press lever fulcrumed on said frame and having a second pressing element thereon; a rod adapted to be reciprocated longitudinally of the lever; a roller on said rod bearing against the upper surface of said lever; means for reciprocating said rod; a yoke pivoted at one end to said frame; yieldable means connecting the other end of said yoke to said frame; and means on said yoke adjacent said yieldable means for guiding said roller when said second pressing element is in pressing relation with said

130

135

140

145

150

fixed pressing element to effect a heavy pressure on said second element.

11. A garment press comprising in combination a frame; a fixed pressing element; a movable pressing element fulcrumed on said frame and adapted to be moved into pressing relation with said fixed pressing element; power means; pressure applying means; a clutch for connecting said power means and the pressure applying means; means normally holding said clutch inoperative; a control member movable with said pressing element for moving said clutch into power applying position; and means on said frame engaging said control member to prevent actuation thereof until said member is moved out of engagement with said last-mentioned means by a predetermined movement of said movable element.

12. A garment press comprising in combination a fixed pressing element; a movable press lever having a second pressing element thereon; power means; means adapted to coact with the upper surface of said lever for applying pressure to said second pressing element; means for connecting said power means to said pressure applying means; and means to prevent the connection of said power means and pressure applying means except when said second pressing element has been moved a predetermined distance with respect to said fixed element.

13. A garment press comprising in combination a frame; a fixed pressing element; a movable pressing element fulcrumed on said frame and adapted to be moved into pressing relation with said fixed pressing element; power means; pressure applying means; a clutch for connecting said power means and the pressure applying means; means normally holding said clutch inoperative; a rockable lever for actuating said clutch; and an abutment on said frame to prevent said lever from being rocked and the clutch actuated except when said movable element has been moved a predetermined distance with respect to said fixed element.

45

14. In a garment press, the combination of a fixed frame; a buck thereon; a head; a head-carrying lever fulcrumed on the frame; a member secured to the frame, said member lying in spaced relation to the head-carrying lever, said lever and member being formed with oppositely disposed converging tracks; and means movable in reference to and cooperating with said tracks to rock the head-carrying lever.

80

15. In a garment press, the combination of a main frame; a pair of pressing elements, one fixed on the frame; a movable support for the other of said elements; and pressure applying means comprising rectilinearly reciprocable wedging mechanism acting on said support to move the same and carry the pressing element supported thereby into pressing relation with the other pressing element, said wedging mechanism including a guide member movable relatively to said frame and secured thereto by a yielding element.

90

16. In a garment press, the combination of a main frame; a pair of pressing elements, one fixed on the frame; a movable support for the other of said elements; and pressure applying means comprising rectilinearly reciprocable wedging mechanism acting on said support to move the same and carry the pressing element supported thereby into pressing relation with the other pressing element, said wedging mechanism including a guide member movable relatively to said frame and secured thereto by a yielding element.

105

17. In a garment press, the combination of a fixed frame; a buck thereon; a head; a head-carrying lever fulcrumed on the frame; a member secured to the frame, said member lying in spaced relation to the head-carrying lever, said lever and member being formed with oppositely disposed converging tracks; a yieldable connection between said frame and said member; and means movable in reference to and cooperating with said tracks to rock the head-carrying lever.
